US00D837674S

(12) **United States Design Patent** (10) **Patent No.:** **US D837,674 S**
(45) **Date of Patent:** **** Jan. 8, 2019**

(54) **BAND**(71) Applicant: **Apple Inc.**, Cupertino, CA (US)(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)(73) Assignee: **Apple Inc.**, Cupertino, CA (US)(***) Term: **15 Years**(21) Appl. No.: **29/596,962**(22) Filed: **Mar. 13, 2017****Related U.S. Application Data**

(63) Continuation of application No. 29/578,797, filed on Sep. 23, 2016, now Pat. No. Des. 781,171, which is a continuation of application No. 29/559,671, filed on Mar. 30, 2016, now Pat. No. Des. 768,025, which is a continuation of application No. 29/556,094, filed on

Feb. 26, 2016, now Pat. No. Des. 768,030, which is a continuation of application No. 29/523,808, filed on Apr. 14, 2015, now Pat. No. Des. 750,524, which is a continuation of application No. 29/519,392, filed on Mar. 4, 2015, now Pat. No. Des. 753,008, which is a continuation of application No. 29/498,994, filed on Aug. 11, 2014, now Pat. No. Des. 727,198, which is a continuation of application No. 29/498,994, filed on Aug. 11, 2014, now Pat. No. Des. 727,198.

CLAIM

The ornamental design for a band, as shown and described.

DESCRIPTION

FIG. 1 is a bottom front perspective view of a band showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof showing the band in an environment in which it may be used.

The broken lines in the figures show portions of the band and environment that form no part of the claimed design.

1 Claim, 6 Drawing Sheets

FIG. 1

FIG. 2

FIG. 3

FIG. 4

FIG. 5

It is certified that error appears in the above-identified patent and that said Letters Patent is hereby corrected as shown below:

On the Title Page

Please replace the "Related U.S. Application Data" item (63) with the following:

Continuation of application No. 29/578,797, filed on Sep. 23, 2016, now Pat. No. Des. 781,171, which is a continuation of application No. 29/559,671, filed on Mar. 30, 2016, now Pat. No. Des. 768,025, which is a continuation of application No. 29/556,094, filed on Feb. 26, 2016, now Pat. No. Des. 768,030, which is a continuation of application No. 29/523,808, filed on Apr. 14, 2015, now Pat. No. Des. 750,524, which is a continuation of application No. 29/494,994, now Pat. No. Des. 727,198. Said application No. 29/559,671 is a continuation of application No. 29/519,392, filed on Mar. 4, 2015, now Pat. No. Des. 753,008, which is a continuation of application No. 29/498,994, filed on Aug. 11, 2014, now Pat. No. Des. 727,198.

Signed and Sealed this
Eleventh Day of May, 2021

Drew Hirshfeld
